UNITED STATES PATENT OFFICE.

CHARLES G. PERKINS, OF HARTFORD, AND ELLSWORTH A. LA HAR, OF NEW BRITAIN, CONNECTICUT, ASSIGNEES, BY DIRECT AND MESNE ASSIGNMENTS, TO PERKINS CORPORATION, OF HARTFORD, CONNECTICUT, A CORPORATION OF CONNECTICUT.

CUPPING-DIE.

SPECIFICATION forming part of Letters Patent No. 783,889, dated February 28, 1905.

Application filed June 4, 1904. Serial No. 211,214.

To all whom it may concern:

Be it known that we, CHARLES G. PERKINS, residing at Hartford, and ELLSWORTH A. LA HAR, residing at New Britain, in the county of Hartford and State of Connecticut, citizens of the United States, have invented a new and useful Cupping-Die, of which the following is a specification.

This invention relates to a die which is particularly designed for cupping paper, but is applicable for cupping other material.

The object of the invention is to provide a simple, cheap, and efficient die for cupping stiff paper and the like fibrous material or any material which has such a nature that it requires crimping before it can be cupped.

The embodiment of the invention that is illustrated by the accompanying drawings has a female die with spirally-arranged scoring-ribs, a male die with corresponding spirally-arranged scoring-ribs, and a punch with spirally-arranged grooves that after the male and female dies have scored the blank forces the scored blank with a spiral movement through the female die for the purpose of cupping it.

Figure 1 of the views shows a vertical central section of the dies, punch, and their supporting parts. Fig. 2 shows a side elevation of these parts. Fig. 3 shows a side elevation of the punch. Fig. 4 shows a side elevation of a modified punch. Fig. 5 shows a view of the upper face of the die-bed and the female die. Fig. 6 shows a view of the under face of the male die. Fig. 7 shows a view of the upper face of the male die, and Fig. 8 shows a view of the under face of the thrust-block.

The die bed 1, which may be formed of iron or steel, as desired, has a longitudinal slot 2 at one end and a transverse slot 3 at the other end for the bolts which are used to fasten it in position. The female die 4, which is annular in outline, is set in a recess in the upper part of the die-bed. The upper face of this die slopes downwardly toward the central opening and is grooved, so as to provide a large number of spiral ribs. The under face of the male die 5, which is annular in outline and slopes upwardly and outwardly, is grooved, so that it has a large number of spiral ribs. When

the male and female dies come together, the 50 spiral ribs on one part extend between the spiral ribs on the other part, so as to score with spiral crimps whatever material is between them. The male die is supported by screw-studs 6, which extend loosely through perforations in the thrust-block 7 and turn into threaded sockets in the upper face of the male die. Springs 8 are arranged between the under face of the thrust-block and the upper face of the male die, so as to normally thrust the 60 male die from the thrust-block. The heads of the studs limit the amount of separation of the male die and the thrust-block. When the thrust-block is forced downwardly, the male and female dies come together and score the 65 outer portion of the blank between them.

The punch 9 has a shank 10, that extends through the thrust-block and the sleeve 11, which projects upwardly from the thrust-block, and is held in position by a nut 14, that is screwed upon the upper threaded end of the shank. Between the punch and a ball-case 12 in a recess in the thrust-block are balls 13. These balls take the thrust between the thrust-block and the punch and relieve 75 the friction to such an extent that while being thrust downwardly the punch may also be rotated on its axis. In the side wall of the punch, which extends loosely through the male die, are a number of spiral grooves 15, 80 into which extend balls 16, that are placed in sockets in the male die. The position of these balls may be adjusted by set-screws 17, that turn in the male die. When the male and female dies come together on the blank, the 85 springs yield and the punch continues its downward movement through the male and female dies. The balls, which are supported by the die and extend into the spiral grooves in the punch, cause the punch to rotate as it 90 descends. The punch is provided with a large number of small spiral grooves 18, which correspond with the spiral scoring-ribs of the male and female dies, so that the portion of the blank which is scored by the male and female dies will when it is carried spirally 95 downwardly by the punch through the female die crimp into the grooves and allow the

formation of a cup. A point 19 may be arranged at the lower end of the punch for the purpose of extending through an opening in the blank and centering it before the male 5 and female dies come together. Studs 20 may be arranged in the side of the male die in position to engage posts 21 on the face of the die-bed for limiting the downward movement of the male die.

- 10 The balls in the male die could be left out and the screws turned in, so that their inner ends would extend into the grooves and cause the punch to move spirally when it moves independently of the male die. If desired, the 15 balls and screws in the male die and the spiral grooves for receiving the balls in the wall of the punch can be dispensed with, in which case the punch would be as illustrated in Fig. 4. In this case if the crimping-grooves 20 respond as to size and angle with the scoring-ribs of the male and female dies the scoring-creases by engagement with these crimping-grooves will cause the punch to move spirally when it is forced down by the thrust-block. 25 This cupping-die is particularly adapted for cupping thick paper or sheets of fibrous material which are used for insulating parts of electrical devices and appliances, although it is applicable for cupping blanks of other material. By reason of the spiral movement of the punch the blank which is scored by the male and female dies is crimped compactly and firmly without materially affecting its structure when it is forced down through the 30 female die by the punch.

The invention claimed is--

1. A cupping-die having a female die, a male die adapted to be moved toward and from the female die, and a punch adapted to 40 be moved spirally from the male die into the female die, substantially as specified.

2. A cupping-die having a spirally-ribbed female die, a spirally-ribbed male die adapted to be moved toward and from the female die, 45 and a punch adapted to be moved from the male die into the female die, substantially as specified.

3. A cupping-die having a spirally-ribbed female die, a spirally-ribbed male die adapted 50 to be moved toward and from the female die, and a spirally-grooved punch adapted to be moved from the male die into the female die, substantially as specified.

4. A cupping-die having a female die, a male 55 die adapted to be moved toward and from the female die, and a spirally-grooved punch adapted to be moved from the male die into the female die, substantially as specified.

5. A cupping-die having a spirally-ribbed 60 female die, a spirally-ribbed male die adapted

to be moved toward and from the female die, a spirally-grooved punch adapted to be moved from the male die into the female die, and means for giving the punch a rotation when it is moved independently of the male die, substantially as specified. 65

6. A cupping-die having a female die, a male die adapted to be moved toward and from the female die, a punch adapted to be moved from the male die into the female die, 70 and balls arranged between the male die and the punch for giving the punch a rotation when it is moved independently of the male die, substantially as specified.

7. A cupping-die having a die-bed, a female 75 die located in the die-bed, a thrust-block, a male die supported by the thrust-block, springs normally forcing the male die from the thrust-block, studs guiding and limiting the movement of the male die with relation to 80 the thrust-block, a punch supported by the thrust-block and extending into the male die, and means for rotating the punch when it is forced from the male die into the female die, substantially as specified. 85

8. A cupping-die having a die-bed, an annular female die located in the die-bed, a thrust-block, an annular male die supported by the thrust-block, springs normally forcing the male die from the thrust-block, studs guiding 90 and limiting the movement of the male die with relation to the thrust-block, a spirally-grooved punch supported by the thrust-block, balls arranged between the punch and the thrust-block, and means for causing the punch 95 to move spirally when it is forced from the male die into the female die, substantially as specified.

9. A cupping-die having a die-bed, an annular female die located in the die-bed, a thrust-block, an annular male die supported by the thrust-block, a punch extending through the male die and having a stem extending through the thrust-block, antifriction-balls between the punch and the thrust-block, a nut on the 100 end of the stem of the punch for holding the punch and the thrust-block together, and means for causing the punch to move spirally 105 when it moves independently of the male die, substantially as specified. 110

10. A cupping-die having a ribbed female die, a ribbed male die, a grooved punch, and means which cause the punch to move spirally when it moves independently of the male die, substantially as specified.
